UNDERGARMENT

Ernst Richard Meinig, Reading, Pa.

Application June 14, 1934, Serial No. 730,557

1 Claim. (Cl. 2—78)

This invention relates to an under-garment and has for its primary object the provision of an under-garment having a brassière and panty connected together as a unitary article, an elastic strip being secured to the free edge of the brassière and a second elastic strip secured to the under-garment at the point of juncture of the brassière and panty so that the brassière may be tightly drawn about the bust of the wearer to support the same.

An object of the invention resides in locating resilient strips at the top and bottom portions of the brassière so as to support the bust and prevent the same from dropping below the brassière.

Another object of the invention resides in knitting a brassière and a panty as a unitary structure from elastic yarn and plain yarn so as to have a maximum degree of stretch and locating at required points additional elastic strips that cooperate to more effectively fit the brassière of the garment around the body of the wearer.

A feature of the invention resides in providing a pair of spaced elastic strips in the construction of the brassière so as to stretch the latter tightly around the body of the wearer.

Besides the above, my invention is distinguished in constructing a combination brassière and panty of a single knitted back section and a single knitted front section cut to required shape and sewed to complete the panty and the brassière, and arranging an elastic strip around the entire free edge of the brassière and an elastic strip at the point of juncture of the brassière with the panty.

With these and other objects in view, the invention will be better understood from the following detailed description taken in conjunction with the accompanying drawing, wherein:

Figure 1 is a perspective view of the under-garment in applied position.

Figure 2 is a diagrammatic view of a portion of the fabric.

Figure 3 is a sectional view on the line 3—3, Figure 1.

Referring particularly to Figure 1, the garment is illustrated as constructed from a back section fabric (1) and a front section fabric (2) the two fabrics preferably knitted from elastic yarns

and plain yarns, as diagrammatically illustrated in Figure 2, the elastic yarns being diagrammatically illustrated by the heavy lines (3), and the plain yarns being diagrammatically illustrated by the light lines (4).

The back section fabric (1) and the front section fabric (2) are cut to the required shape and seamed, to provide the brassière (5) and the panty (6). To the free edge (7) of the brassière, I stitch an elastic strip (8) and this strip passes entirely around the under-garment and has attached thereto the shoulder straps (9).

A second elastic strip (10) is stitched to the under-garment at the point of juncture of the brassière with the panty and this strip is only passed part way around the garment so as to have a more effective contracting action upon the lower portion of the brassière.

The locations of the elastic strips are such that the fabric forming the brassière (5) is neatly drawn around the body of the wearer and this elastic effect of the strips in conjunction with the elasticity of the body fabrics assures a neat fitting garment; and the contracting of the upper and lower portions of the brassière around the bust prevents the dropping thereof.

Having described my invention, what I claim is:

An under-garment comprising an upper section including a brassière and body portion, and a lower section consisting of a pair of panties said sections being connected together as a unit and knitted from interposed plain yarn and elastic yarn, the elastic yarn acting to impart an increased transversal tautness to the entire garment to make the same close form-fitting; an elastic strip extending continuously around the upper edge of the brassière and adapted to snugly engage the body of the wearer above the breasts to anchor the garment; and a second elastic strip disposed at the connection between the body portion and the brassière and extending only around the front of the garment to tighten the latter at that point located immediately below the breasts and thus provide a fullness in the brassière.

ERNST RICHARD MEINIG.
